UNITED STATES PATENT OFFICE.

EDWARD MEAKER PEARSON, OF WHEELING, WEST VIRGINIA.

DESIGN FOR A DISH.

SPECIFICATION forming part of Design No. 20,118, dated August 26, 1890.

Application filed May 29, 1890. Serial No. 353,668. Term of patent 7 years.

To all whom it may concern:

Be it known that I, EDWARD MEAKER PEARSON, a citizen of the United States, residing at Wheeling, in the county of Ohio and State 5 of West Virginia, have invented a new and useful Design for Dishes, of which the following is a specification.

The leading feature of my design is the equilateral curvilinear triangle, which is formed 10 by the edges of my dish, its cover, or by any horizontal plane cut through my dish.

In the accompanying drawings, illustrating 15 my invention, Figure 1 is a plan view of a vegetable dish, showing my design. Fig. 2 is a plan view of the cover. Fig. 3 is a view of the dish and cover in side elevation, and Fig. 4 is a view of the same in section.

In the drawings, A designates a vegetable-dish, soup-tureen, or other receptacle having 20 its sides a gently sloping upward and outward from the bottom a' . Near the top of these sides a a ledge a^2 is formed, and from thence the sides curve at a great angle outward to the edges a^3 . These edges may be 25 scalloped or ornamented, as shown, or plain curves; but the essential feature is that they should form an equilateral curvilinear triangle.

The corners A' , formed in the dish at the 30 meeting of the side a , are not sharp indentations, such as would be made in describing an equilateral curvilinear triangle on paper,

but are gently rounded, though this is not essential. The outside of the sides a gently slope from the edges a^3 to the feet a^4 , one at 35 each angle. These may be ornamented, as shown, or in any manner, or left plain. The under side of the bottom a' at the edges between the feet a^4 may be curved upward, like a bracket, , as shown. 40

The lid B to this dish is of the same contour—that is, its edges b , when viewed in plan, form an equilateral curvilinear triangle. The angles may be ornamented, as shown. The lid B has an ornamental handle b' , the arms 45 of which are in the relative position to each other of the longer radii of an equilateral triangle.

What I claim is—

1. The design for a dish, as herein described 50 and shown, which consists in the same having gently-curving sides ending in edges which form an equilateral curvilinear triangle.

2. In a design for a dish, herein described and shown, the cover having a contour of an 55 equilateral curvilinear triangle.

In testimony that I claim the foregoing as my own I have hereto affixed my signature in presence of two witnesses.

EDWARD MEAKER PEARSON.
